United States Patent

Des. 238,341

Patented Jan. 6, 1976

238,341

DIGITAL WRISTWATCH

Arthur Cruse, Dallas, Tex., assignor to
E. Gluck Corporation, New York, N.Y.

Filed Aug. 16, 1974, Ser. No. 497,944

Term of patent 14 years

Int. Cl. D10—02

U.S. Cl. D10—38

FIG. 1

FIG. 2

FIG. 3

FIG. 4

FIG. 5

FIG. 6

FIG. 1 is a top plan view of a wristwatch showing my new design;

FIG. 2 is a bottom plan view thereof;

FIG. 3 is a front elevational view thereof;

FIG. 4 is a rear elevational view thereof;

FIG. 5 is a left side elevational view thereof; and FIG. 6 is a top, front, and right side perspective view thereof.

I claim:

The ornamental design for a digital wristwatch, as shown and described.
